STRIP FOR TERRAZZO AND SIMILAR FLOORS

Filed Feb. 8, 1930

UNITED STATES PATENT OFFICE

PASQUALE GALASSI, OF NEW YORK, N. Y.

STRIP FOR TERRAZZO AND SIMILAR FLOORS

Application filed February 8, 1930. Serial No. 426,883.

This invention relates to pattern or dividing strips for use in floors made of plastic material such as terrazzo, granolithic, stucco and cement floors for preventing the opening of cracks in the surface of the floor and also for producing novel and ornamental floor designs.

More particularly the invention refers to a novel and improved dividing strip forming a hollow chamber adapted to receive a filler which may be preformed or poured into place and which may preferably be made of material imparting to the floor anti-slip properties.

15 Terrazzo, granolithic and similar floors usually comprise a foundation bed, or layer of concrete, cement, mortar or other suitable material, and a superposed layer usually composed of small pieces of marble, mixed with 20 a suitable bonding agent, such as cement.

After the foundation layer has been allowed to harden to a sufficient degree of consistency, it becomes possible to place in position the upper layer which is generally divided into geometrical or ornamental units in the form of panels or blocks which are obtained by outlining the desired design by means of strips placed on or inserted through the under bed, or attached thereto.

30 The dividing strips which are left permanently in position and constitute an integral part of the finished floor, adding to its attractiveness by producing novel designs, at the same time localizing cracks which may 35 occur in the floor panels, are generally made of thin flat bars of relatively soft metal such as brass, set on edge within the floor composition, the upper edge of said bars being flush with the surface of said floor.

40 In a patent entitled Methods of and means for producing anti-slip terrazzo floorings, issued to me January 7, 1930, #1,742,855, I have described floor strips comprising a hollow head portion forming a longitudinal chamber within which is retained a suitable 45 filler, and a thin rib portion depending from said head portion, said rib portion being preferably provided with anchoring and positioning means adapted to determine the 50 placement and retention of the strip in its

proper position with respect to the floor material.

In another patent entitled Flooring strip issued to me January 14, 1930, #1,743,814, I have described another type of strip in which a head made entirely of anti-slip material such as lead or cement composition is provided with a thin metal rib portion depending therefrom.

The main object of the inventions described by said two patents is to provide terrazzo and similar floors having anti-slip properties, the strips used in said floors being of the pre-formed variety.

I have found that in practice it is at times preferable to use strips which are more suitable for the pouring of the anti-slip or other composition or material after the strip has been placed in position. I have also found that it is possible to simplify to a certain extent the construction of strips of the type described in my patent #1,742,814, so as to reduce their cost of production and also their weight, by making it possible to pour the anti-slip material or composition after the strip has been laid in place. At the same time the type of strip forming the subject of the present invention may also be considered as being an improvement over the strips described and claimed in my copending application entitled Dividing strips, Ser. No. 247,620, said application referring to preformed floor strips made of cementitious material; inasmuch as the present strip comprises a filler which may be preformed and reinforced by an external metallic shell, or else may be poured within the shell and allowed to harden so as to form a unitary strip with said shell before it is used.

The primary object of this invention is to provide a new and improved type of dividing strip for terrazzo and like floors, adapted to form new and attractive designs and also adapted when desired to impart anti-slip properties to the floor.

Another object is to provide a floor dividing strip which can be produced at relatively low cost, although it is suitable for use in floors where relatively wide dividing strips between adjoining panels should be used.

A further object is to provide a novel type of anti-slip dividing strip for terrazzo and similar floors adapted to be made in unitary form or to be completed after being laid 5 in place according to conditions governing each particular case.

Other objects and advantages of the present invention will more fully appear as the description proceeds and will be set forth and 10 claimed in the appended claims.

My invention is illustrated by way of example in the accompanying drawing, in which:

Fig. 1 is a fragmentary view in perspective 15 of the shell portion of a strip embodying my invention;

Fig. 2 is a cross sectional elevation thereof through line 2—2 of Fig. 1;

Fig. 3 is a fragmentary view in perspective 20 of the shell portion of a strip of a somewhat different design, also embodying my invention;

Fig. 4 is a fragmentary sectional view in perspective of a terrazzo floor showing the 25 shell of a strip embodying my invention in position previous to the pouring of the filler therein;

Fig. 5 is a fragmentary sectional elevation 30 of the same floor after cement or cement composition has been poured within the shell in order to complete the strip;

Fig. 6 is a fragmentary sectional elevation 35 of a terrazzo floor comprising dividing strips somewhat similar to that illustrated in Figs. 4 and 5;

Fig. 7 is a fragmentary sectional elevation 40 of a terrazzo floor illustrating a shell somewhat similar to that shown in Fig. 3 in position previous to the pouring of the filling material;

Fig. 8 is a fragmentary sectional elevation 45 of a terrazzo floor comprising strips somewhat similar to that illustrated in Fig. 7;

Fig. 9 is a fragmentary sectional elevation 50 of a terrazzo floor comprising strips of another design also embodying my invention;

Fig. 10 is a fragmentary sectional elevation 55 of a terrazzo floor showing the shell of a still different strip in position previous to filling;

Fig. 11 is a fragmentary sectional view in perspective of a terrazzo floor illustrating the shell of a strip of still different design, in position previous to the pouring of the 60 filler therein;

Fig. 12 is a fragmentary sectional elevation 65 of a terrazzo floor illustrating another design of strip also embodying my invention; and

Fig. 13 is a fragmentary view in perspective 70 of a strip embodying my invention in unitary form, said strip being made complete with filler and shell before being used.

My improved strip comprises essentially 75 an open top shell made of suitable material such as brass for instance, filled with a plastic

material or composition or with a core of different metal or wood. The strip may be made complete in unitary form together with the filler, this being especially the case when a metal or wood filler is used; or else when 70 a plastic material or composition is used for the filler, the strip may be made complete in unitary form before used or else the shell may be placed in position and then the filling material may be poured within the same 75 and subsequently allowed to harden.

In this case the filler may consist of cement or concrete or cement composition, or asphalt or else it may preferably consist of an anti-slip aggregate adapted to impart to 80 the floor anti-slip properties. It is, of course, also within the scope of this invention to use as a filler soft metal such as lead for instance, which may be poured in position after the shell has been laid. Among the soft metals, 85 lead is particularly suitable also on account of its anti-slip properties.

The shell illustrated in Figs. 1 and 2 is formed out of a relatively long and narrow flat strip of light gauge metal bent along its 90 longitudinal central line to form a U-shaped structure having two parallel sides 20, 21 and a preferably pointed lower end 22. A pointed lower end facilitates the insertion of the shell through the plastic material out 95 of which the lower layer of the floor is made and also results in less material being needed for the filler.

It is customary in dividing strips to provide anchoring means adapted to retain said 100 strips in position, said anchoring means being preferably so placed that they may be used also as positioning means determining the depth at which the strip is to be placed. The shell just described may accordingly be 105 provided with anchoring or positioning means or both of any suitable description; for instance, ears or lugs such as 23, 24 may be struck off its sides at spaced intervals and bent outwardly therefrom. If said ears or 110 lugs are bent at right angle to the vertical plane of the strip, and are spaced from the upper edges of the shell a distance equivalent to the thickness of the upper layer of the floor, they may serve as positioning means 115 and will also determine the correct vertical alignment of the strip or shell when it is placed in position.

If desired, some of the ears or lugs may be 120 bent inwardly instead of outwardly as shown at 25 so as to provide anchoring means for the filling material within the shell; and in this case it is also preferable to make said lugs 25 as wide as the chamber 26 provided for the filler between sides 20, 21, so as to 125 maintain the proper distance between the sides and enable said sides to resist the lateral pressure due to the floor material adjoining them. Instead of making the shell with parallel sides the sides may be made up- 130

wardly converging as shown in Fig. 3 where the shell is composed of two upwardly converging sides 27, 28 and pointed bottom 29, said sides being provided with anchoring and 5 positioning means 30, 31 if desired.

In Figs. 4 and 5 I illustrate a terrazzo floor comprising a foundation bed 32, a lower floor bed 33 and an upper or finishing layer 34. After the lower bed 33 has been laid in position and is still in a plastic condition, the strip shell 35 which is of the type illustrated in Figs. 1 and 2 with or without the inner ears or lugs 25 is inserted within said lower bed previous to the laying of the upper layer.

15 When this is done it is preferable to cover the open top of the shell, with a longitudinal plug as shown at 36. This has the double advantage of preventing the floor composition from entering the shell and holding the 20 edges of the shell at the proper distance, so as to enable the sides to resist the lateral pressure of the floor material, even if no internal lugs or ears such as 25 are provided.

After the floor material has hardened, the 25 plug 36 is removed and the filling material 37 is poured within the shell as shown in Fig. 5 and allowed in its turn to harden before the floor is finally scraped, finished and polished to completion.

30 In Figs. 4 and 5 the shell is shown deep enough to reach the level of the foundation bed of the floor. In practice, this is not strictly necessary because when positioning means of a suitable type are provided, it is 35 sufficient to insert the shell or strip through the lower bed of the floor only to a depth such as determined by the positioning means. For instance, in Fig. 6 where 38 is the foundation bed, 39 is the lower layer of the floor and 40 40 is the upper layer, I illustrate a strip, the shell of which 41 only reaches about midway of the depth of the lower bed, its depth of insertion within said lower bed being determined by the anchoring and positioning lugs 45 such as 42 which are spaced from the upper surface of the strip a distance equivalent to the depth of the upper layer 40.

In all these cases as stated, the filling material may be poured after the shell has been 50 inserted in position or else the strip may be completed first in unitary form including both the shell and the filler and may then be placed in position in this form.

In Fig. 7 I illustrate a floor comprising a 55 foundation bed 43, a lower floor bed 44 and an upper layer 45, said floor comprising strips, the shell of which has a pointed bottom 46 and two upwardly converging sides 47, 48. Like in the case illustrated in Fig. 4, 60 said shell may be laid in position equipped with a longitudinal plug 49 maintaining the proper distance between the upper edges of the shell. This type of strip does not require anchoring means such as shown in the preceding figure because the converging sides are

sufficient to prevent its coming off the floor after the floor material becomes hard.

Positioning means of any suitable type however may be provided if desired, for instance in the form of ears or lugs such as 70 previously described, or else in the form of longitudinal beads or impressions such as 50 spaced from the upper edges of the shell a distance equivalent to the thickness of the upper layer of the floor.

75 Positioning means of the type projecting from the sides of the shell are preferable when the depth at which the shell is to be inserted through the lower bed of the floor is to be determined entirely by said positioning means. This is the case for instance in the strip illustrated in Fig. 8 where the lower end 51 of the shell does not reach the level of the floor foundation 52, its depth of insertion being determined by the laterally 80 extending lugs or ears 53 reaching the upper surface 54 of the lower layer or bed of the floor 55.

85 The proper positioning of the strip or shell may also be determined by the shell's own outline, if desired. For instance, in Fig. 9, the sides of the shell are shown formed with upper upwardly converging portions 56, 57, and lower portions 58, 59 inwardly raised therefrom to form shoulders 60, 61, 90 which are spaced from the upper edges of the shell a distance equivalent to the thickness of the upper layer 62 of the floor. A similar result may be obtained by using the strip illustrated in Fig. 10 where the sides of the shell comprise two upper parallel bars 63, 64 and two lower parallel bars 65, 66 joined by a pointed lower end 67, said lower portions being outwardly offset from the upper portions to form shoulders 67, 68 at a 95 distance from the upper edges of the shell corresponding to the depth of the upper floor layer 69.

100 The shell 70 illustrated in Fig. 11 is somewhat similar to that illustrated in Fig. 4 except that the upper ends 71, 72 of the sides of the shell converge inwardly, thus preventing the filler from coming loose.

115 Another strip in which the shell outline may be used to determine the depth of insertion of the strip is illustrated in Fig. 12. In the same the shell is composed of a vertical side 73 and another side having a lower portion 74 and an upper portion 75, outwardly inclined to meet at a point 76 spaced from the upper end of the strip a distance corresponding to the depth of the upper layer 77 of the floor. In this type of strip the apex 76 at one side acts as positioning means and the anchoring function is provided by the inward inclination of the upper portion 75 of said side.

120 In order to illustrate the different types of materials which may be used to produce a filler in Fig. 5 I show cement as being used, while in Fig. 6 the filler is made of asphalt, in 125

Fig. 8 it is made of metal, preferably lead, and in Figs. 9, 12 it is made of cement composition or anti-slip aggregate.

In Fig. 13 I illustrate the possibility of making the strip complete in unitary form including the shell and the filler before use, the strip shown comprising a shell 78 of the type illustrated in Fig. 3 and a filler 79 which may be of any suitable material as listed above, the material specifically illustrated being a cement composition or anti-slip aggregate.

It will be observed that in every case, the strip provides a two color effect which affords a convenient means of increasing its decorative possibilities; therefore the filling material used may be selected purely from the standpoint of ornamental or else from the standpoint of its anti-slip properties, or both.

From the foregoing it will be seen that my inventive idea may be applied in a number of ways. The drawing will therefore be understood as being intended for illustrative purposes only and not in a limiting sense. Accordingly, I reserve the right to carry my invention into practice in all those ways and manners which may enter, fairly, into the scope of the appended claims.

I claim:

1. A dividing strip for terrazzo and like floors comprising in unitary form an open top metal shell adapted for insertion within plastic material, said shell extending for the entire depth of the strip, a filler filling the space within the shell and means for anchoring said filler within said shell.

2. A dividing strip for terrazzo and like floors comprising in unitary form an open top metal shell adapted for insertion within plastic material, said shell extending for the entire depth of the strip, and being narrower at the mouth than intermediate its top and bottom edges, and a non-yielding filler filling the space within the shell flush with the top thereof.

3. A dividing strip for terrazzo and like floors comprising in unitary form an open top metal shell adapted for insertion within plastic material, said shell extending for the entire depth of the strip, anchoring and positioning means projecting laterally of said shell, a filler filling the space within the shell and anchoring means for said filler integral with and projecting inwardly of said shell intermediate the top and bottom thereof.

4. A dividing strip for terrazzo and like floors comprising in unitary form an open top metal shell adapted for insertion within plastic material, said shell extending for the entire depth of the strip, anchoring and positioning means projecting laterally of said shell, a filler filling the space within the shell and spacing means integral with and extending between the sides of said shell intermediate the top and bottom thereof, said spacing

means also acting as anchoring means for said filler.

5. A dividing strip for terrazzo and like floors consisting of a lower layer made of plastic material and an upper layer made of a plastic material having a different composition, comprising an open top metal shell extending for the entire depth of the strip adapted for insertion within said lower floor layer while in its plastic form, said shell being provided with laterally projecting positioning means spaced from the upper edge of said shell a distance equivalent to the thickness of the upper layer of the floor, said positioning means determining the depth at which the shell is to be inserted within the lower layer.

6. A dividing strip for terrazzo and like floors consisting of a lower layer made of plastic material and an upper layer made of a plastic material having a different composition, comprising an open top metal shell extending for the entire depth of the strip adapted for insertion within said lower floor layer while in its plastic form, said shell being provided with laterally projecting positioning means spaced from the upper edge of said shell a distance equivalent to the thickness of the upper layer of the floor, said positioning means determining the depth at which the shell is to be inserted within the lower layer, and a non-yielding filler of anti-slip material in said shell flush with the top surface of said floor.

7. A dividing strip for terrazzo and like floors consisting of a lower layer made of plastic material and an upper layer made of a plastic material having a different composition, comprising an open top metal shell extending for the entire depth of the strip adapted for insertion within said lower floor layer while in its plastic form, said shell being provided with laterally projecting positioning means spaced from the upper edge of said shell a distance equivalent to the thickness of the upper layer of the floor, said positioning means determining the depth at which the shell is to be inserted within the lower layer, and a non-yielding filler in said shell, and means for anchoring said filler in said shell.

8. A dividing strip for terrazzo and like floors consisting of a lower layer made of plastic material and an upper layer made of a plastic material having a different composition, comprising an open top metal shell adapted to contain anti-slip material, said shell extending for the entire depth of the strip adapted for insertion within said lower floor layer while in its plastic form, said shell being provided with laterally projecting positioning means spaced from the upper edge of said shell a distance equivalent to the thickness of the upper layer of the floor, said positioning means determining the depth at

which the shell is to be inserted within the lower layer, and means integral with said shells extending between the sides thereof to maintain the sides of the shell in spaced relation against the plastic material.

5 9. A dividing strip for terrazzo and like floors comprising in unitary form an open top metal shell adapted for insertion within plastic material, said shell extending for the entire depth of the strip, and a core of anti-slip material within said shell flush with the top thereof.

10. A dividing strip for terrazzo and like floors consisting of a lower layer made of plastic material and an upper layer made of a plastic material having a different composition, comprising an open top metal shell extending for the entire depth of the strip adapted for insertion within said lower floor 15 layer while in its plastic form, said shell being provided with laterally projecting positioning means spaced from the upper edge of said shell a distance equivalent to the thickness of the upper layer of the floor, said positioning means determining the depth at which 20 the shell is to be inserted within the lower layer, a core of anti-slip material within said shell flush with the top thereof, and means 25 for anchoring said core within said shell.
